(57) **CLAIM**

The ornamental design for an egg carton as shown and described.

DESCRIPTION

FIG. 1 is a frontal perspective view of the egg carton when the egg carton is in a closed configuration.

FIG. 2 is a rear perspective view of the egg carton seen in FIG. 1 when the egg carton is in an open configuration.

FIG. 3 is a front elevation view of the egg carton when the egg carton is in the closed configuration.

FIG. 4 is a rear elevation view of the egg carton when the egg carton is in the closed configuration.

FIG. 5 is a right side elevation view of the egg carton when the egg carton is in the closed configuration.

FIG. 6 is a top plan view of the egg carton when the egg carton is in the closed configuration; and,

FIG. 7 is a bottom plan view of the bottom portion of the egg carton when the egg carton is in the closed configuration.

The broken lines are shown for the purpose of illustrating parts of the article which form no part of the claimed design.

1 Claim, 4 Drawing Sheets
